Application May 23, 1957, Serial No. 661,222

4 Claims. (Cl. 251—49)

This invention relates to a flushing device that is adapted to be operatively connected with a toilet bowl in order to replace the open tank.

An object of the invention is to provide a sealed and comparatively noiseless flushing device which may be built in the toilet bowl or located adjacent to the toilet bowl. The flushing device consists essentially of a sealed container which encloses a movable sleeve valve in which a piston is slidable. Through an organization of locks and springs, water under pressure of the system augmented by spring pressure, is caused to flow into the toilet bowl. After a sufficient charge of water passes into the bowl, causing complete flushing, the device automatically resets and then recycles in response to the pressure of the water in the water supply system of the town, city, etc. In this way the flushing device automatically readies itself for subsequent flushing.

A further object of the present invention is to provide a practical flushing device which is both rapid and very quiet, the flushing device being of such construction that it is easily manufactured and occupies a small volume. The water handled in the flushing device is caused to flow very promptly into the toilet bowl after the flushing handle is actuated.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a view in elevation schematically representing one suggested installation of a flushing device constructed in accordance with the invention;

Figure 2 is a vertical sectional view of a flushing device of my invention, the device being shown in a position where it would be filled with water and ready for a flushing operation;

Figure 3 is a transverse sectional view taken on the line 3—3 of Figure 2;

Figure 4 is a fragmentary sectional view showing the upper part of the flushing device of Figure 2 as it would appear shortly after turning the actuating handle to the flush position; and

Figure 5 is a sectional view of the flushing device showing the parts in the relative positions that they will occupy when the flush operation has been almost completed, the parts being arranged where they would appear just prior to the closing of the discharge port of the device by the sleeve valve.

In the accompanying drawings there is a toilet bowl 10 which is intended to be typical of any manufacturer's make and type of presently used toilet bowl. Flushing device 12 which exemplifies the invention, is shown mounted at the back of the toilet bowl 10 and with a line (unshown) that would be operatively connected to the back of the toilet bowl to conduct the flush water

2

thereinto. It is to be clearly understood that flushing device 10 need not necessarily be mounted in this location with respect to the toilet bowl 10 but may be built in the toilet bowl and may be remote therefrom with a longer pipe line leading from the device 12 to the toilet bowl water inlet.

Device 12 consists of a container 14 that has a side wall 16 (preferably cylindrical) and a bottom wall 18 connected to the side wall 16. Vent 20 is formed in the bottom wall in the spring lug 22 on which coil spring 24 is seated. The upper wall 26 of container 14 has an inlet 28 which is adapted to connect to the local source of water under pressure, as by pipe line 30. Top wall 26 also has an opening through which spindle 32 passes, this spindle having an operating handle 34 attached to it. The handle has a bonnet 36 at one end which houses spring 38, the latter reacting on an inner surface of bonnet 36 and an ear plate 40 that is attached to top wall 26 thereby providing the necessary friction that offers resistance to free spinning movement of the handle 34. Packing is around spindle 32 to prevent leakage at this location. A flushing water discharge pipe 44 is registered with the water outlet 46 that is formed in the side wall 16 of container 14. This water pipe 44 is adapted to operatively connect with the toilet bowl 10 in the manner previously described.

Sleeve valve 50 is vertically reciprocably disposed in the container 14 and if necessary, piston rings are located between the inner surfaces of wall 16 and the outer surface of the sleeve valve 50. Stop 54 in the form of a collar, is mounted at the top of container 14 and is adapted to be abutted by the sleeve valve 50 when the same is being elevated by the pressure of spring 52. This limits the extent of upward travel of sleeve valve 50.

The top wall 60 of sleeve valve 50 has a plurality of openings 61 in it or is formed of a framework, grill or a foraminous panel. Upwardly opening well 62 is in the top wall 60 of valve 50 and forms a seat for spring 54 which reacts not only on valve 50 but also on the top wall 26 of container 14. A transverse pin 66 extends across a central aperture 67 in top wall 60 of sleeve valve 50. Cam surfaces 72 formed along the side walls of a slot in socket 74 at the lower end of spindle 32, are used for rotating the handle as sleeve valve 50 is elevated until the handle is locked in place by pin 66 coming to rest on a land in the slot. Conversely, when the handle 34 is manually rotated to flush the toilet, pin 66 is separated from its land thereby enabling spring 64 which is now in the compressed state, (Figure 2) to push valve 50 downward in container 14 thereby opening port 46.

Two latches 78 and 80 are attached to the top wall 26 and extend downwardly into container 14. These latches are made of material capable of being sprung outwardly (Figure 5) but able to return to the initial position (Figure 2). Certain grades of spring steel or other metal are suitable for this purpose. The latches have stops 81 and 82 formed on the inner surfaces thereof and cam surfaces 85 and 86 above the stops 81 and 82.

Piston 88 is mounted for reciprocation in the bore 89 of sleeve valve 50. If considered necessary or desirable piston rings may be applied on the piston to preserve a proper substantially liquid tight seal between the valve and the piston. There is a downwardly opening cup 90 formed in the bottom of the piston 88 in order to seat the spring 24. The function of the spring is to push the piston 88 upward (Figure 5) when water pressure from above has been reduced. An annular cam 91 is formed around the clearance hole 92 in the center of

piston 88, annular cam 91 being adapted to come into contact with cam surfaces 93 and 94 formed at the end of locks 78 and 80 and spread these locks to release the top wall 60 of sleeve valve 50 from engagement therewith and allow the top wall together with the remainder of sleeve valve 50 to be elevated by the stored energy in spring 52 (Figure 5).

In operation, attention is directed first to Figure 2 which shows the flushing device fully charged with water and ready to be actuated. Actuation is caused by rotating handle 34, thereby releasing pin 66 from the cam lock at the lower end of spindle 32. The stored energy in spring 64 pushes the sleeve valve 50 downward in container 14 and thereby opens the port 46. Water from the water inlet pipe 30 is then capable of flowing across the top inner part of container 14 and through discharge port 46.

As the sleeve valve 50 moves in a downward direction, a small part 97 of the top wall 60 of sleeve valve 50, rides over the cam surfaces 85 and 86 of the locks 78 and 80, spreading the locks apart. The valve 50 moves down far enough so that the part 97 snaps beneath the stops 81 and 82 of locks 78 and 80 thereby retaining the sleeve valve 50 in the open position.

At the time of this action, the pressure on the upper surface of piston 88 is relieved by opening valve port 46. This relief of pressure enables the stored energy in spring 24 to lift the piston upwardly thereby emptying the water supply from within the bore 39 of sleeve valve 50 and pushing it through discharge port 46. This additional water augments the supply of water which passes from inlet pipe 30 and flows through port 46. Such additional water assures that complete and proper flushing of the trap in the toilet bowl 10 takes place.

When the piston 88 reaches the upper extremity of its travel (Figure 5) the annular cam 91 spreads the locks 78 and 80 causing the stops 81 and 82 thereof to become separated from part 97 of the top wall 60 of sleeve valve 50. In attaining this height, piston 88 compresses spring 52 against the lower surface of the top wall 60 of valve 50, and when the locks 78 and 80 are released, the stored energy in the compressed spring 52, pushes the valve 50 upward and in the valve port 46 closing position (Figure 2). At the same time the pin 66 is pushed into the cam lock, riding on the cam slot 72 and becoming disposed in the land thereof. This automatically resets the actuating handle, closes valve port 46 and enables the water under pressure to enter port 28 and again depress piston 88 which automatically recharges the container with a supply of water preparatory to another flushing operation.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A flushing device for a toilet bowl, said flushing device comprising a container having an inlet port and an outlet port, a sleeve valve movably disposed in said container and arranged to control said outlet port, a piston slidably disposed in said sleeve valve, said piston being exposed to the pressure of the water of said inlet port, a spring reacting on said piston and compressed by said pressure whereby upon release of said pressure said spring pushes said piston in a direction to displace the water and move the water through said discharge port and when said sleeve valve is moved to a discharge port opening position, means carried by said container and operable from the exterior thereof for releasably locking said sleeve valve in the discharge port closing position, and a spring reacting on said sleeve valve to push said sleeve valve to the discharge port open position in response to release of said locking means.

2. A flushing device for a toilet bowl, said flushing device comprising a container having an inlet port and an outlet port, a sleeve valve movably disposed in said container and arranged to control said outlet port, a piston slidably disposed in said sleeve valve, said piston being exposed to the pressure of the water of said inlet port, a spring reacting on said piston and compressed by said pressure whereby upon release of said pressure said spring pushes said piston in a direction to displace the water and move the water through said discharge port and when said sleeve valve is moved to a discharge port opening position, means carried by said container and operable from the exterior thereof for releasably locking said sleeve valve in the discharge port closing position, a spring reacting on said sleeve valve to push said sleeve valve to the discharge port open position in response to release of said locking means, said sleeve valve having an apertured top wall, a sleeve valve return spring reacting on the bottom surface of said top wall of said sleeve valve and contactable by said piston when said piston is elevated, thereby to return said piston to the valve discharge port closing position, and means including at least one lock for holding said sleeve valve in the discharge port open position until said lock is released by the upward movement of said piston.

3. The combination of claim 2 wherein said lock comprises a flexible member carried by said container and having a stop against which a part of said top wall of said sleeve valve is adapted to seat.

4. The combination of claim 3 wherein there is a cam on the upper surface of said piston which is engageable with said flexible member to push said flexible member in a direction to separate said stop from said part of said wall of said sleeve valve.
